UNITED STATES PATENT OFFICE.

FRANK P. STEIL, OF CUDAHY, WISCONSIN.

GAUNTLET.

Application filed December 12, 1921. Serial No. 521,739.

To all whom it may concern:

Be it known that I, FRANK P. STEIL, a citizen of the United States, and resident of Cudahy, in the county of Milwaukee and 5 State of Wisconsin, have invented certain new and useful Improvements in Gauntlets; and I do hereby declare that the following is a full, clear, and exact description thereof.

My invention relates to a gauntlet of new 10 and improved structure and its object is more particularly to provide a structure whereby a free flexure of the wrist is permitted and yet the wristlet is held in its proper shape without becoming wrinkled.

15 My invention is illustrated in the accompanying drawing, in which:—

Figure 1 is a plan view of a gauntlet constructed in accordance with my invention, and

20 Figure 2 is a sectional view on the line 2—2 of Figure 1.

In the drawing the numeral 5 designates the hand portion of the gauntlet to which the 25 wristlet 6 is secured by stitching. A stiffening lining 7 is provided for the wristlet in order to hold the same in the desired shape. In the embodiment of my invention shown in the drawing this stiffening extends over the entire back half of the wristlet but is cut 30 away for a portion of its length on the front side as shown at 8. This stiffening while it maintains the wristlet in its proper shape permits the easy flexure of the wrist by reason of its being cut away at the point

35 where the greatest bending would occur.

The gauntlet is preferably completed by the usual finishing flap 9 which protects the seam connecting the wristlet with the hand portion. The upper edge of the wristlet is finished by a binding strip 10. While I have 40 shown one application of my invention it will be understood that the principle of the invention may be carried out in connection with other gauntlets of other styles than that shown. It is also within the scope of my invention to cut away the lining 7 all the way around the wrist instead of across the front portion 8 only.

I claim as my invention:—

A gauntlet having a hand portion, a wrist- 50 let secured thereto, said wristlet being continuous throughout its extent on both its front and back from its outer edge to the hand portion, a stiffening lining for the wristlet extending from the hand portion 55 throughout the back half of the wristlet and across the outer front half of the wristlet and on the forward side of the wristlet being spaced from said hand portion, and a line of stitching joining said hand portion and 60 wristlet, whereby a wristlet of unbroken continuity and stiffened throughout its back portion and the outer portion of the front is provided.

In testimony that I claim the foregoing I 65 have hereunto set my hand at Cudahy, in the county of Milwaukee and State of Wisconsin.

FRANK P. STEIL.
